UNITED STATES PATENT OFFICE.

HENRY S. HALLWOOD, OF COLUMBUS, OHIO.

STREET-PAVEMENT.

SPECIFICATION forming part of Letters Patent No. 400,767, dated April 2, 1889.

Application filed November 16, 1888. Serial No. 291,023. (No model.)

To all whom it may concern:

Be it known that I, HENRY S. HALLWOOD, a citizen of the United States, residing at Columbus, in the county of Franklin and State of Ohio, have invented a certain new and useful Improvement in Street-Pavements, of which the following is a specification.

My invention relates to the construction of street-pavements, and the objects of my invention are to provide a superior foundation for streets and street-railways which shall be simple in construction, inexpensive and durable, and which shall form a superior bed for paving-blocks of uniform solidity; to combine with said foundation a paving-surface consisting of suitable paving-blocks so formed and arranged as to present a durable and uniform traveling-surface having suitable footholds therein; to so construct my improved pavement as to prevent the individual settlement or sinking of the paving-blocks and the formation of ruts; to provide a firm and secure foundation for street-railway tracks; to obviate, when desired, the necessity of using cross-ties or chairs in the construction of said railways and present a foundation for the same which shall be impervious to the action of atmospheric influences, and to so form and arrange the paving-blocks adjoining the rails of street-railways as to prevent injury thereto by the contact therewith of the wheels of heavy vehicles. These objects I accomplish in the manner illustrated in the accompanying drawings, in which—

Figure 1 is a transverse section of my improved pavement wherein is laid the street-railway track. Fig. 2 is a view in perspective of a portion of my improved pavement, showing the railway-track combined therewith; and Fig. 3 is a perspective view of one of the paving-blocks.

Similar letters refer to similar parts throughout the several views.

The crown of the street having been formed of the desired convexity by excavation, rolling, or otherwise, upon the earthen surface of the street thus shaped is first laid transversely of the street a covering of boards, *b*, the latter having been first tarred or otherwise preserved from the action of the atmosphere. In case a street-railway is to be constructed upon said street, two parallel lines, *d*, of

plank are laid longitudinally upon said board covering *b*. These plank lines *d* are laid respectively beneath the projected lines of track-rails. Upon the planks *d* thus laid are seated and secured by spikes made to penetrate the planks, or the planks and boards, the flanged base of the metallic rails *f*. Upon the planks *d*, and on each side thereof, is then placed a covering, *c*, preferably consisting of gravel or of broken stone, or of a mixture of both, said layer being preferably of such depth as to be equal to or slightly greater than the height of the track-rail base-flanges and having its upper surface shaped to conform to the contour of the street-crown.

g represents the paving-blocks, which are preferably of what is known as "vitrified clay," but may be of any desired hard substance, said blocks being, as shown, laid in such manner as to break joints. These paving-blocks are adapted to be laid, as shown, upon the bed of gravel or broken stone, *c*. Upon those sides of each of these blocks at right angles with the upper and lower sides are formed rows of continuous horizontal grooves or corrugations *i*, encircling said blocks, for the purpose hereinafter specified, and each of said blocks preferably has its upper edges beveled, as shown.

As shown in the drawings forming a part of this application, the above-described paving-blocks are laid between the railway-tracks, as well as on each side thereof. Those blocks adjacent to each side of the tracks are made to approximately interlock with said rails by having their ends shaped to conform to the shape of the standard street-railway track-rail sides.

For the purpose of promoting clearness in my description I will designate those blocks adjoining the outer sides of the track-rails by the reference-letter *f'* and those adjoining the inner sides of said rails as *f''*. These rail-blocks *f'* *f''* are for the purpose hereinafter mentioned so set as to leave a slight space, *h*, between the same and the rail. The paving-blocks are of such height as to project a short distance above the track-rails, as shown. The upper surface of the inner track-block, *f''*, is for a short distance from the track-rail depressed until in line with the surface of the bearing-flange of the track, while the upper

edges of the track-blocks f' on the side toward the track are beveled, as shown.

The herein-described paving-blocks are so laid as to leave slight spaces between them, 5 said spaces being filled by pouring therein liquid pitch, cement, or other similar matter, which enters into the encircling corrugations or grooves i , thereby firmly uniting the blocks. The spaces h between the track-rails and 10 blocks f', f^2 are also similarly filled, thus firmly embedding the rails between the paving-blocks.

By the above-described construction it will be seen that a firm, compact, and durable 15 pavement-foundation is afforded in a comparatively simple and inexpensive manner, and that the uniform arrangement of each section and the superior character of the material used will obviate any tendency of a portion 20 of the pavement to sink, and thus form depressions and irregularities in the surface.

The peculiar method herein described of combining the building of a street-railway with the pavement construction affords the 25 advantages of providing a solid bed for the entire base of each of the rails and may obviate the use of chairs and cross-ties and prevents the tendency of the rails to sag or bend laterally. The V-shaped depressions between 30 the paving-blocks formed by the bevels of the upper edge thereof will greatly facilitate the gaining of a foothold on the pavement. The depressed surface of the rail-blocks f^2 adjoining the rail will admit of the running thereon 35 of a wide-tired wheel without injury to the pavement or track.

I am aware of the patent to Virgil A. Gates and Mordicai Levi, of September 25, 1883, No. 285,746, wherein a layer of boards is made 40 to rest upon a bed of sand. It will be observed that in the herein-described foundation the boards are brought into direct contact with the earthen surface of the street, thus causing the weight of the pavement to

fall flatly upon the soft earth beneath and 45 thereby obviating any tendency of the pavement to settle in part or wholly, which might be caused by the sinking of the gravel, sand, or other similar material heretofore used as a base for the foundation.

I am also aware that paving-blocks have been made with horizontal grooves extending over only a portion of their sides, and I do not claim said construction.

Having now fully described my invention, 55 what I claim, and desire to secure by Letters Patent, is—

1. A rectangular paving-block having in its sides continuous horizontal grooves or corrugations encircling said blocks and the upper 60 edges beveled, substantially as and for the purpose described.

2. The combination, in a street-pavement, of the street-railway rails f , the adjoining paving-blocks f' , so set as to have their beveled top upon a higher level than the top of the rail, the blocks f^2 having one half of their surface depressed in line with the surface of the bearing-flange of the track and the other half having their tops upon a higher level 70 than the top of the rail and the inner ends or sides adjoining said rails conforming to the shape of the web and flanges of the rail, but with an opening between them alongside the flange and the web of the rail wherein pitch 75 is poured, substantially as described.

3. In a street-pavement and railway-track, the combination of the layer of boards b , planks d laid thereon, railway-track rails f , secured to said planks and boards, as described, and the layer of gravel, sand, or broken stone, c , upon said planks and boards, with the paving blocks or bricks resting upon said layer c , substantially as described.

HENRY S. HALLWOOD.

In presence of—

C. W. ALLISON,
C. C. SHEPHERD.
